ACTUATOR FOR RECIPROCATING RAZOR

Harold A. Swan, Coronado, Calif.

Application September 9, 1957, Serial No. 682,673

7 Claims. (Cl. 30—42)

This invention relates generally to razors and more particularly to an actuator mechanism for causing controlled, slow reciprocation of a razor blade.

Prior art devices for actuation of razor blades have been characterized by either too rapid movement of the blade or insufficient control of the blade movement and this invention seeks to correct these deficiencies.

It is a primary object of this invention to provide a safety razor construction wherein a blade holder is satisfactorily reciprocated in the direction of the cutting edge of the razor blade so that a transverse or sliding action is achieved to improve the cutting efficiency of the blade, but with perfect control such as will avoid injury to the underlying skin, provided the razor is used in the proper manner. This primary object may also be considered as including provision of actuator means having a minimum number of moving parts and with these parts completely enclosed.

Another object of this invention is to provide an actuator for a razor of this general type wherein force achieved as a result of finger pressure on the handle or body portion of the razor is transmitted virtually directly to the blade holder, giving instantaneous movement to the blade holder in response to and in proportion to such finger pressure.

Still another object of this invention is to provide an actuator which, by reason of its ultimate simplicity, will give durable service without virtually any maintenance or repair, except possibly the replacement of a pressure capsule after a period of use of several years.

With these objects definitely in view, along with other objects which will appear hereinafter as this description proceeds, this invention consists in the novel construction, combination and arrangement of elements and portions, as will be hereinafter fully described in the specification, particularly pointed out in the claims, and illustrated in the drawing which forms a material part of this disclosure, and in which:

Figure 1 is an end view of a razor incorporating my invention and the illustrated end of the razor will be considered the top of the razor for purposes of this disclosure;

Figure 2 is a central, vertical sectional view, except for those portions of the mechanism and blade holder plate which are disposed close to the center line, these portions being shown in elevation; and

Figure 3 is a side elevational view of the razor and may be considered as taken from the right hand side of Figure 2, the portion of the head being broken away to show underlying portions in elevation and in cross section.

Similar characters of reference indicate similar or identical elements and portions throughout the specification and throughout the different views of the drawing.

Referring now to the drawing in detail, this invention is comprised of four principal parts which may be considered the handle 10, the head, generally indicated by the numeral 12 and enclosing the principal parts of the

2

mechanism, the blade holder 14 and the blade 16, the last element being represented as being of the double-edged type, although it will be obvious that the invention can be incorporated in razors employing various types of blades.

The head 12 is somewhat elongated as will be readily evident from a comparison of Figures 2 and 3, with reduced wing portions 20 and a thicker central portion 22. The head 12 is provided with a screwed neck 24 whereby it is connected to the handle 10. The head also includes a unitary platform portion 26 in encompassing relation, and the platform portion, at the sides of the head, constitutes a support for blade guards 28 which are of angle-plate character.

15 A well 30 is provided in one of the reduced wing portions 20 and extends from the top of the head 12 to a point close to the lower end of the head. This well 30 houses one leg 31 of a U-shaped strap 33, the bight portion 34 of which bridges the central portion of the head. 20 The lower ends of the legs 31 and 32 are provided with barrel bearings 36 which accept machine screws 38, whereby the bight portion 34 is rendered capable of parallel motion with reference to a plane through said machine screws 38, it being understood that the U-shaped strap 33 is somewhat flexible and resilient. Bosses 40 may be found on opposing sides of the reduced wing portions 20 to provide better support for the ends of the machine screws 38. These machine screws 38 function as journals for the barrel bearings 36.

25 A cavity 42 is provided in the head 12 and occupies the principal central portion thereof. This cavity 42 extends from the wall 43, defining one side of the well 30, to a point close to the upper end of the head 12 and the leg 32 of the U-shaped strap 33 occupies that portion of the cavity 42 remote from the well 30. A capsule 44 is seated between the well 30 and the leg 32 of the U-shaped strap and a neck 46 of the capsule extends downwardly into a bushing 48. The bushing 48 has an outwardly turned flange 50 which is held by the shoulder 30 52 of the handle 10, a gasket 54 being inserted between the shoulder and the flange 50.

30 At the upper end of the head 12, an arched member 56 is secured in abutting relation to the upper edge of the capsule 44. As illustrated, the central portion of the arched member 56 extends downwardly into the cavity 42 and one end 58 of the arched member is retained in substantially fixed relation to the upper end portion 59 of the wall 43. The other end 60 of the arched member is in continuous engagement with the U-shaped strap 33 adjacent the junction of the bight portion 34 and the leg 32. A slot 62 is provided in the under, central surface of the blade holder 14 and the bight portion 34 is fixed in this slot 62. It will be obvious from the foregoing that straightening of the arched member 56 will cause a movement, as to the right in Figure 2, of the bight portion 34 and the blade holder 14, which moves therewith.

35 The blade holder consists of a body member 64 of generally rectangular plan form with a large rectangular recess 66 on the underside thereof, defined by depending flange-like portions 67 which encompass the said opening. On the top of the body member 64, there is provided an upstanding, elongated rib 68, dimensioned to be received in the central opening of a razor blade 16, and a razor blade clamp plate 70 is pivoted, as at 72, 40 in the depending flange-like portions 67, at one end of the body member 64, as clearly indicated in Figures 1 and 2. As illustrated, the clamp plate 70 is also elongated and centrally apertured to receive the upstanding rib 68. A snap clip 74 is provided on the end of the clamp plate, 45 remote from the pivot 72 and this snap clip engages a projection 76 on the adjacent portion of the depending

flange-like portion 67 to hold the clamp plate in closed position, thereby retaining the blade 16 in operative position.

On the top of the head 12 I provide an upstanding wall 77, extending above the level of the platform portion 26 a distance substantially equal to the depth of the recess 66. This wall 77, along with the platform portion 26 and adjacent portions of the blade holder 64, define a chamber encompassing the upper portion of the head 12 and within the blade holder 64 and this chamber is filled with sponge rubber or the like which can be considered a flexible, resilient gasket 78. The function of the gasket 78 is to prevent entry of foreign materials into the head 12, while permitting a reciprocating movement of the blade holder relative to the head. It will be recalled that the blade holder is supported solely by the bight portion 34 of the U-shaped strap 33, although the platform 26 functions as a stop to limit any tilting of the blade holder relative to the head.

Since the fluid 82, as will be explained more fully immediately herebelow, can cause deformation of the arched member 56 in one direction and the driving of the blade holder in one direction only, it is preferred that the U-shaped strap will be so formed as to assume the position indicated in Figure 1 when at rest and under no-pressure conditions. This will assure return of the U-shaped strap to this position, but further assurance for the return of the strap and the blade holder 14 to the positions shown in Figure 2 is provided in the form of the coiled spring 80 compressed between an upper end portion of one leg 32 of the U-shaped strap and the upper end portion 59 of the wall 43.

The structure of the handle is simple. The main portion of the handle is a hollow elongated cylinder of somewhat flexible and very resilient material, several plastic materials being suitable, and a ferrule 88 is provided at the upper end of the handle to reinforce the threaded portion thereof engaged with the neck 24. A gasket 90 is interposed between the ferrule 88 and the adjacent portion of the head 12. Another ferrule 92 is used to reinforce the lower end of the handle 10, which is closed by an external and internal threaded end plug 94. A fill plug 96 is screwed into this end plug 94 and a sealing gasket 98 completes this assembly.

The operation of this invention will be clearly evident from a consideration of the foregoing description of the mechanical details thereof. In recapitulation, finger pressure on the handle 10 causes a displacement of the fluid 82 from the handle 10, through the bushing 48, into the capsule 44. Pressure exerted by the capsule 44 creates an upwardly directed force against the arched member 56, tending to straighten the same, thereby effecting translation of the end 60 of the arched member, since the end 58 thereof is substantially fixed relative to the head 12. In passing, it should be noted that the end 58 may conveniently be merely inserted in a simple notch in the upper end wall portion 59. Movement of the end 60 causes a like movement of the bight portion 34 and the blade holder with the blade 16 therein. Upon release of the finger pressure upon the handle 10, the natural resiliency of the U-shaped strap 33 and the coiled spring 80 assures return of the blade holder and blade to the original positions, as illustrated in Figure 2. The bight portion 34 has a depending stop portion 100 formed therein, said stop portion extending toward the arched member 56 and preventing that member from snapping over center when straightened out by the fluid pressure. It will be obvious that reciprocation of the blade 16 is thus accomplished at the option of the user of the razor and at the exact speed which he desires. The legs of the U-shaped strap have very little side or edge clearance in the well 30 and the cavity 42 and this limits or prevents tilting or transverse motion of the blade holder. It will be understood that the legs 31 and 32 will ordinarily be of the same width as the bight portion 34, in the interest of

economical production, and transverse width of the well 30 and cavity 42 will be only slightly greater than the said uniform width of the legs, as indicated in Figure 3. It will, of course, be understood that the user will probably always find it advantageous to employ different speeds of reciprocation of the blade while shaving different portions of the face.

Minor variations from the form disclosed may be resorted to without departure from the spirit and scope of this invention and the present disclosure is declared as being illustrative rather than limiting.

I claim:

1. In a safety razor: a head having a blade holder mounted thereon for reciprocation relative thereto; means to reciprocate said blade holder comprising a resilient, elongated arched member having one end thereof substantially fixed against movement in one direction relative to said blade holder and having the other end thereof operatively engaged with said blade holder; and means for periodically straightening said arched member to move said one end and said blade holder.

2. In a safety razor: a head having a blade holder mounted thereon for reciprocation relative thereto; means to reciprocate said blade holder comprising a resilient, elongated arched member having one end thereof substantially fixed against movement in one direction relative to said blade holder and having the other end thereof operatively engaged with said blade holder; and means for periodically straightening said arched member to move said one end and said blade holder; means engaging said blade holder to bias the same toward movement in one direction, and said one end pushing said blade holder in the opposite direction when said member is straightened.

3. In a safety razor: a head having a blade holder mounted thereon for reciprocation relative thereto; means to reciprocate said blade holder comprising a resilient, elongated arched member having one end thereof substantially fixed against movement in one direction relative to said blade holder and having the other end thereof operatively engaged with said blade holder; and means for periodically straightening said arched member to move said one end and said blade holder; the last mentioned means including a hollow element capable of expansion in one direction, under increased internal pressure and operatively mounted in said head to press against one side of said member to effect said straightening; and means for periodically increasing said internal pressure.

4. In a safety razor: a head having a blade holder mounted thereon for reciprocation relative thereto; means to reciprocate said blade holder comprising a resilient, elongated arched member having one end thereof substantially fixed against movement in one direction relative to said blade holder and having the other end thereof operatively engaged with said blade holder; and means for periodically straightening said arched member to move said one end and said blade holder; the last mentioned means including a hollow element capable of expansion in one direction under increased internal pressure and operatively mounted in said head to press against one side of said member to effect said straightening; and means for periodically increasing said internal pressure; said hollow element being a flexible, resilient capsule; the last mentioned means being a hollow, flexible and resilient handle communicating with said capsule and constituting therewith a closed, fluid-filled system.

5. In a safety razor: a head having a blade holder; a U-shaped strap having a bight portion and legs terminating in bearing elements whereby the legs are converted to said head for rocking movement about axes in a single plane; said blade holder being fixed to the bight portion of said U-shaped strap for parallel reciprocatory movement of the blade holder with reference to said plane; a resilient, arched member having one end thereof

substantially fixed against movement in one direction relative to said blade holder and having the other end thereof operatively engaged with said blade holder; and means for periodically straightening said arched member to move said one end and said blade holder.

6. The combination of claim 5 wherein the last mentioned means includes a flexible, resilient capsule operatively mounted in said head to press against said arched member, and a hollow, resilient handle communicating with said capsule and constituting therewith a closed, 10 fluid-filled system.

7. The combination of claim 5 wherein said U-shaped strap has its bight portion adjacent to said arched member, and said bight portion has a portion projecting toward said arched member and disposed to prevent the 5 arched member from over-center movement.
